Jack N. Kaiser, Louisville, Ky., assignor to American Radiator & Standard Sanitary Corporation, New York, N.Y., a corporation of Delaware

Original design application Oct. 23, 1965, Ser. No. 87,833, now Patent No. 207,249, dated Mar. 28, 1967. Divided and this application Feb. 21, 1967, Ser. No. 5,911

Term of patent 14 years

(Cl. D4—2)

Fig. 1.

Fig. 2.

FIG. 1 is a perspective view of a sink showing the new design;

FIG. 2 is a side view thereof, the portion of the sink shown in broken lines being omitted for convenience of illustration.

The dominant features of my design reside in the portions shown in full lines, and the faucet fixtures shown in FIG. 2 are included for illustrative purposes only.

This is a division of design application Serial No. 87,833, filed October 23, 1965, now Design Patent No. 207,249.

I claim:

The ornamental design for a sink, substantially as shown and described.
